Primary Examiner — Paula Greene(74) *Attorney, Agent, or Firm* — Middleton Reutlinger; Robert H. Eichenberger; Chad D. Bruggeman(57) **CLAIM**

The ornamental design for an organizer for a listening device, substantially as shown and described.

DESCRIPTION

FIG. 1 is a front perspective view of the organizer; FIG. 2 is a top or bottom view of the organizer according to FIG. 1, the two views being identical;

FIG. 3 is a front or back view of the organizer according to FIG. 1, the two views being identical;

FIG. 4 is a left or right side view of the organizer according to FIG. 1, the two views being identical;

FIG. 5 is a front perspective view of the organizer according to FIG. 1 shown with exemplary environment such as, but not limited to, a listening device and associated wire;

FIG. 6 is a front perspective view of an alternative organizer; and,

FIG. 7 is a front or back view of the organizer according to FIG. 6, the two views being identical. It is to be understood that the top or bottom view of the organizer according to FIG. 6 would be identical to the view shown in FIG. 2. It is also to be understood that the left or right side view of the organizer according to FIG. 6 would be identical to the view shown in FIG. 4.

Portions of the organizer for a listening device and any exemplary environment shown in broken lines are for illustrative purposes only and form no part of the claimed design.
